Filed Nov. 27, 1961, Ser. No. 155,082
22 Claims. (Cl. 100—4)

This invention relates to improvements in performed loop type binding machines wherein a length of wire is fed into an oval raceway or guide track to form a loop about a bundle and then stripped from the guide track and tensioned and secured on the bundle.

This type of binding machine overcomes certain disadvantages and limitations of the more common type of machine where the wire is laid under tension about a bundle by a revolving ring. As the bundles become ever larger and the wire heavier and stiffer, difficulties are encountered in feeding and tensioning the wire at high speed, ring velocities become excessive, power requirements for starting and stopping the ring become excessive and automatic control of the machine functions becomes more difficult. These factors impose limitations on the capabilities of ring type machines of large size as a result of which it is found that ring type machines cannot be ever increased in size and speed to meet the increasing demands of industry.

Also, the revolving ring type machines are not adaptable to perform all the functions desired of a binding machine. For example, a ring machine cannot thread a wire through pallet runner openings on the bottom of a box for binding such a box transversely of its pallet runners. Again, the ring machines are not well adapted to bind a box in a horizontal plane. It is often desired to bind a large shipping box with a plurality of bands in each of three different directions applying vertical transverse bands, vertical longitudinal bands and horizontal bands.

In a preformed loop type of machine there are no large or heavy parts to be started in motion and stopped in each cycle of operation. Regardless of the size of bundle the only power requirement is to feed and tension the wire itself—a body of relatively low inertia and momentum. The control mechanisms are few and simple. The wire feed and tensioning operations are performed as well in horizontal as vertical positions and the wire may be fed through pallet runner openings. In longitudinal and horizontal banding the wire feed may be completed while the bundle is moving into binding position. The machine is light and compact, having few moving parts and no ponderous parts moving at high speed. Much of the mechanism may be standardized for application to machines of different size; a variation in the size of bundle opening does not call for complete redesign of the whole machine. The problem of re-threading the wire from a new coil or spool is completely eliminated. Although the present mechanisms are designed for use with round wire, they may also be adapted for use with oval wire or flat strap.

Previous attempts to make performed loop wire type machines have not been entirely successful because the wire would not strip from the guide track in a manner to result in uniform tension in the wire around all sides of the bundle. Even though the wire would be drawn extremely tight on one side of the bundle, it would remain loose on the opposite side. This characteristic has heretofore limited this type of machine to relatively small sizes, using small and relatively flexible wire. This type of machine has not heretofore been used successfully for large and heavy bundles and boxes requiring stiff wire

and wire which must be drawn back a considerable distance in the process of removing the wire from the guide track and drawing it tight against the sides and around the corners of the package. An important one of applicant's improvements has removed this difficulty whereby the machines may now be made to any size desired.

The general object of the invention is to provide an improved preformed loop type of binding machine.

Another object is to provide improvements in the guide track to control the release of the wire so that the wire will be tensioned substantially uniformly all around the bundle.

Another object is to provide improved means to accommodate overrun in the feed movement of the wire into the guide track and to provide improved control means responsive to such overrun for stopping the feed movement.

Another object is to provide an improved arrangement of guide track and fastening head so that the fastening head itself will serve as a bundle clamp.

Another object is to provide a machine capable of applying a plurality of horizontal bandings around a bundle at different levels.

Another object is to provide a machine which will bind a box through openings in its pallet runners.

Still other objects are to provide improvements in the details of construction and control mechanisms for machines of the class described, to provide a machine of better reliability with lower service and maintenance requirements and to provide a greater standardization of parts than has heretofore been found.

For the purpose of illustrating the principles of the invention, three different machines are utilized to bind a large box or shipping container in three different directions. The box selected as an example is equipped on its bottom with longitudinal pallet runners spaced by blocks below the bottom of the box to travel on a roller conveyor system. The pallet runners are preferably wide enough so that they will also travel freely transversely over the conveyor rollers. The box approaches the first binding machines with its pallet runners longitudinal to the direction of travel. The guide track of the first binding machine is disposed in a vertical plane transverse to the line of travel and has gaps in its lower side to admit the pallet runners. The plane of the guide track thus determines the plane of the binding, the guide track having a central opening forming a bundle passage. The bundle is stopped in position to receive a first transverse binding through its pallet openings. When the box arrives at this position gates close in the lower side of the guide track, completing the continuity of the wire guide track through the spaces above the pallet runners. A wire is then fed around the guide track and twice through a splicing mechanism in a fastening head on the upper side of the guide track where the end of the wire is secured in a gripper.

At the completion of its feed movement, the end of the wire encounters a stop arresting the movement of the wire around the guide track and causing a yieldable section in the guide track to be deflected outwardly to accommodate overrun while the feed motor is stopping. The guide track gates open and the feed motor reverses immediately, stripping the wire therefrom. The guide frame and fastening head then move downward, causing the fastening head to engage and clamp the top of the box. Reversal of the feed motor strips the wire from the rest of the guide track and tensions it about the box, after which a twister gear from a splice and a cutter severs the wire between the splice and the source of supply. Then the guide frame and fastening head move up to free the box for movement to its next banding position in the same machine. In this way two or more bands are ap-

plied to the box transversely through the pallet openings.

The box then moves off on a second conveyor at right angles to the first conveyor with the pallet runners now disposed transverse to the direction of travel. Alternatively, the box may be rotated through ninety degrees on a turntable and continue in line with the first conveyor. The second binding machine is similarly arranged except that its guide track need not be equipped with gates to pass through the pallet runner openings because now the vertical bindings are to be placed parallel with and between the pallet runners. After the second machine has performed this function, the box passes on to a third machine for horizontal binding.

In the third machine the guide track frame is supported in horizontal position and mounted for vertical movement. When the box arrives at the binding station, its movement is halted on the conveyor and the guide track and fastening head descend to binding position surrounding the box. After a band has been applied about a lower portion of the box, the guide track and fastening head may be arranged to rise automatically to a second binding position and apply another band. When these operations are completed, the guide track and fastening head rise clear of the box and the conveyor carries it away. The box is now fully bound with longitudinal and transverse vertical bands and horizontal bands. The order of the operations may be varied if desired and, when greater speed is necessary, each machine may be equipped with a plural number of guide tracks and fastening heads to apply two or more bands simultaneously in parallel planes instead of applying successive bands in parallel spaced relation with the same machine.

The invention will be better understood and additional objects and advantages will become apparent from the following detailed description of the preferred embodiment illustrated in the accompanying drawings. Various changes may be made, however, in the construction and arrangement of parts and certain features may be used without others. All such modifications within the scope of the appended claims are included in the invention.

In the drawings:

FIGURE 35 is a view similar to FIGURE 32, showing the action of the yieldable guide track section at the completion of the wire feed movement;

FIGURE 36 is a bottom plan view of the guide track shown in FIGURE 35 with the gates in open position;

FIGURE 37 is an exploded diagrammatic view of the cutter, twister gear and gripper at the completion of wire feed movement;

FIGURE 38 is a view similar to FIGURE 35, showing the first stage of wire stripping from the guide track;

FIGURE 39 is a similar view showing the next stage of the wire stripping action;

FIGURE 40 is a view similar to FIGURE 39, showing the wire stripping and tensioning action substantially completed and the fastening head moved down to clamp the box;

FIGURE 41 is a similar view after completion of the wire splicing and cutting operation with the fastening head lifted to free the box;

FIGURE 42 is a diagram of a portion of the electrical and pneumatic systems for the vertical machine shown in FIGURE 1;

FIGURE 42a shows the rest of the diagram in FIGURE 42;

FIGURE 43 is a top plan view of the horizontal machine;

FIGURE 44 is a front elevation view of the horizontal machine; and

FIGURE 45 is a side elevation view of the horizontal machine.

Referring first to FIGURE 3a, there is shown a box B of substantial size having a plurality of pallet runners 10 on its bottom. As an example of the large size of box or bundle handled by the present machine, it is pointed out that the present box is 40 inches high, 72 inches long in the direction of the pallet runners and 56 inches wide. Considering the magnitude of these dimensions it will be apparent that a conventional rotating ring type machine large enough to accommodate such a box would have to have a very large band laying ring which would have to rotate at a rather high peripheral velocity in order to place a plurality of bands on the box in a sufficiently short interval of time to handle a normal work flow. Also, of course, as previously pointed out, a rotating ring type of banding machine could not apply all the bands shown in FIGURE 3a.

Pallet runners 10 are spaced from the bottom of the box by blocks 11 leaving openings 12 to receive the transverse vertical bands or wires W₁ and W₂. Prior to this invention there has been no known automatic machine capable of so applying bands through pallet runner openings under the bottom of the box. The box also carries a plurality of longitudinal vertical bands or wires W₃ and W₄ which extend around the bottom of the box between the pallet runners. Finally, the box is bound by one or more horizontal bands or wires W₅. Ring type binding machines have never been adapted for horizontal binding and, except for possible use in hay baling presses, it may be said generally that horizontal binding machines have never been used commercially for binding boxes and bundles. Thus, in applying the wires W₁ to W₅, the present machines perform new functions that have not been accomplished heretofore in binding boxes, crates and bundles.

Of the three sets of bindings shown in FIGURE 3a, only the wires W₃ and W₄ could be applied by conventional types of machines. No machines are commercially available for applying the horizontal binding W₅ to a box of such size and there are no known machines of any type capable of applying the wires W₁ and W₂. These are the particular problems in the art with which the present invention is chiefly concerned, although the invention is by no means limited in its application to boxes equipped with pallet runners or boxes of the substantial size mentioned.

The machine in FIGURE 1

FIGURES 1 and 3 are general views of the machine for applying the wires W₁ and W₂ transversely through the pallet runner openings 12. The boxes are moved into the machine on a roller conveyor 15 driven by a motor 16 and are carried away from the machine on a roller conveyor 17 driven by a motor 18. Three short roller sections 19 support the pallet runners for a distance between the rear side of the binding machine and the first roller of conveyor section 17. There are open spaces be-

tween the roller sections 19 for a purpose which will presently appear. The machine comprises essentially a large rectangular frame 20 defining a wire guide and bundle opening interposed in a narrow gap between the conveyor sections 15 and 17. The frame 20 is disposed in a vertical plane and mounted on a stationary frame 21 for vertical movement in such plane which may also be referred to as the bundle wrapping plane.

The frame 20 comprises essentially an oval wire guide-way or guide track and a feed motor for pushing a length of wire around the guide track to form a loop surrounding the bundle in the wrapping plane. After the loop has been formed, its leading end is secured in a gripper and the feed means reverses to strip the wire from the guide track and tension it about the bundle. After the wire has been tensioned, portions are connected together on the top side of the bundle and the resulting tensioned loop is cut from the source of supply. In the present machine the wire fastening means comprises a twister gear for forming a twisted wire splice. The twister gear, gripper and cutter are incorporated in a fastening head on the top side of frame 20, which fastening head also functions as a bundle clamp by drawing the top side of the frame down against the top side of the bundle during the wire tensioning and splicing phase of the operation. When the operation is completed, the frame rises sufficiently to clear the bundle for movement to its next banding position or to admit a new bundle.

Frame 20 is raised and lowered by a pair of piston rods 22 in cylinders 23. The upper ends of piston rods 22 are connected to ears 24 on opposite sides of the frame 20 and the lower ends of cylinders 23 are connected to base portions of stationary frame 21.

The wire W is fed into the guide track of frame 20 by a feed mechanism 25 driven by a rotary air motor 26. A pneumatic diaphragm unit 27 operates on the feed mechanism to clamp the wire in frictional driving engagement with a pair of feed rollers. The wire is conducted to this feeding mechanism through a roller straightening assembly 28 from guide sheave 29 above a supply reel 30. In the present instance the reel 30 is driven backward and forward in accordance with the movements of the wire by a reversible electric motor 31. This electric motor is incorporated in a reel holder 32 which supports the reel on edge on a pair of rollers.

Referring now to FIGURE 4, the wire feed mechanism comprises a pair of feed rollers 35 driven by motor 26 and a pair of pressure rolls 36 cooperating therewith. Pressure rolls 36 are mounted on a vertical slide plate 37 actuated by a link 38 connected with the diaphragm of the pneumatic diaphragm unit 27. The wire passes between feed rollers 35 and pressure rolls 36 whereby the traction on the wire may be regulated by adjusting the pressure of the air supply to diaphragm unit 27.

A plate 40 on the upper side of wire guide frame 20 carries the mechanism comprising the fastening head which will also be designated generally by the numeral 40. This fastening head comprises a twister gear T, a single wire gripper G, a single wire cutter C and operating mechanisms for these elements. The lower edge of plate 40 also functions as a bundle clamp which can be brought to bear against the top side of the box. The frame 20 has a wire guide track to guide the incoming end of the wire through the twister gear, around an oval path forming a loop about the bundle and again through the twister gear whereby overlapped portions of the wire may be twisted and spliced together. The entering portion of the wire guide track is a single wire channel 41 extending from the wire feed mechanism to the section 13-13 in FIGURE 4 where the wire guide track becomes a double channel as shown in FIGURE 13.

In FIGURE 13 the incoming wire W_a in channel 41 is separated from the leading end of the wire W_b in channel 42 which has completed its circuit around the guide track, this separation being effected by a division plate 43.

Channel 42 is an open bottom slot in which the wire portion W_b is retained by a plate 44 actuated by a spring 45. Plate 44 has a bevelled edge 46 permitting the wire to push back the plate and escape from channel 42 during reverse movement of the wire when the wire is stripped from its guide track and tensioned about the bundle, as shown in FIGURE 13a. Referring back to FIGURE 4, the double channel wire guide proceeds through plate 40, cutter C, twister gear T, to gripper G where the leading end W_b is intercepted and clamped. From this point on around the wire guide frame 20, the guide track comprises a single channel guideway.

FIGURE 14, which is taken on the line 14—14 of FIGURE 7, shows a cross section of the wire guide track at the approach to the first bend. Here the guide track 41 itself is an open bottom channel in which the wire portion W_a is retained by a plate 47 and spring 48 similar to the plate 44 and spring 45 in FIGURE 13. The bevelled edge of plate 47 permits the wire to strip itself from the channel as shown in FIGURE 14a when it is tensioned around the bundle by reverse feed movement.

The guide track at the first bend comprises a yieldable section 50 which is adapted to deflect outwardly as shown in FIGURES 4 and 7 to accommodate overrun while the feed mechanism is stopping after the movement of the leading end of the wire has been arrested at the gripper G following a complete circuit of the oval track. Track section 50 is pivotally mounted at its trailing end on a pin 51 midway between the top and bottom sides of the track, the upper end of track section 50 being free to swing in a groove 52 of the frame 20. Yieldable section 50 is normally held in register with the upper straight portion of the guide track leading from plate 40 as shown in full lines by an elastic tensioning member 53. When the advancing movement of the leading end of the wire is abruptly halted at gripper G, the resilience of tensioning member 53 allows an excess of wire to push guide track section 50 out to its broken line position in groove 52 with a portion of the wire bridging the gap between the end of section 50 and the preceding fixed section of the guide track. The outward movement of the upper end of section 50 actuates switch LS-6 in FIGURE 4 to stop the feed motor 26 as will hereinafter be explained in detail in connection with the operation of the machine. One of the studs in section 50, presently to be described, extends through arcuate slot 52a and is equipped with a head or flange on the back side of frame plate 20 to hold section 50 against the said frame plate.

Further details of section 50 are shown in FIGURE 12. Section 50 comprises an arcuate bar having a groove 55 defining a channel for the wire W. When section 50 is closed in its normal position, this groove is confronted by a stationary arcuate bar 56 and the intervening space is enclosed by a cover plate 57 comprising a plurality of short leaves having apertures mounted on studs 58 in bar 50. These leaves are pressed resiliently against the faces of the bars 50 and 56 by springs 59 on the studs 58 as shown in FIGURE 12. FIGURE 12a shows the wire stripping action.

Bar 56 terminates in a downwardly tapering ramp end 60 at the extreme end of the oval track adjacent to the position of pivot pin 51 as shown in FIGURE 9. As will be presently explained, the purpose of bar 56 is to prevent stripping of the wire from the first turn of the guide track until it has first been stripped from all the rest of the track. Following this point, the first reverse bend of the guide track takes the form shown in FIGURE 11 which is a cross section on the line 11—11 in FIGURE 7. Bar 61 is similar to bar 50 but is fixed to the plate 20 by studs 62. Groove 63 provides a channel to guide the wire W. This groove is closed by an angular cover plate comprising a plurality of leaves 64 having apertures mounted on the studs 62. These leaves are pressed into the normal position shown in FIGURE 11 by means of springs 65 on the studs 62. The first leaf

in this section of the guide track has its flange portion bevelled as shown at 66 in FIGURE 9 to fit the slope of the ramp 60 on bar 56. The bars 50 and 61 are on the outside of the turn and guide the wire around the oval end of the track during the feed movement. During the reverse feed and wire tensioning phase, the wire is pulled to the inside of the turn causing it to bear against bar 56 and cover leaves 64, the latter yielding to release the wire as will be presently explained in connection with FIGURE 11a. Around the semi-circular bend at the left end of the oval, the guide track is similar to the section shown in FIGURE 11.

The lower side of the guide frame 20 in FIGURE 4 is notched at 69 to receive the pallet runners 10 when the guide frame is in its upper position in FIGURE 1. When the box is in position for binding, the notched openings are closed by gates 70 which carry guide track sections for passing the wires W_1 and W_2 through the openings 12 between the pallet runners and the bottom of the box in FIGURE 3a. Each gate 70 is pivoted on a pin 71 in ears 72 on the guide frame 20 as shown in FIGURES 5 and 6. An arm 73 on the end gate 70 is actuated by a piston rod 74 in a pneumatic cylinder 75. Cylinder 75 is pivotally mounted at 76 on guide frame 20. The other two gates in FIGURE 4 have similar arms 73 which are actuated in unison by a common connecting rod 77.

The gates 70 have guide track sections as shown in FIGURE 10. Each gate has a resiliently mounted cover plate 80 which is normally pressed against one face of the gate by plunger 81 and spring 82. The cover plate has a groove 83 forming a guide channel for the wire W. Closing of the gates takes place simultaneously with the actuation of the wire feed motor 26 which is caused by the operation of bundle operated limit switches to be described presently. Opening of the gates operates limit switch LS-7 in FIGURE 5 which causes the wire feed motor to reverse and start tensioning the wire. The gates open at right angles to the plane of frame 20, parallel with pallet runners 10 as shown in FIGURE 2. The open spaces between short rollers 19 in FIGURE 3 permit the frame 20 to descend with the gates open.

FIGURE 17 is a bottom plan view of a portion of the fastening head as in FIGURE 16, showing the construction and operation of the gripper G. FIGURE 17 shows the gripper in wire receiving position and FIGURE 18 shows the gripper after it has been actuated to clamp the end of the wire. FIGURES 19 to 22 illustrate the details of construction of the gripper.

The gripper G is cylindrical and is journaled for rotation in the gripper block 90. The first pass of the wire from wire guide channel 41 in FIGURE 4 travels through a groove 91 in the gripper and passes around the oval guide track to return through the lower channel 42 in FIGURE 13 as previously explained. This brings the end W_b into the gripper just below the wire portion W_a where it strikes the gripper nose 92, arresting its movement and causing yieldable guide track section 50 in FIGURE 4 to deflect outwardly actuating switch LS-6. As previously explained, the actuation of this switch stops feed motor 26 and actuates the gripper from its FIGURE 17 to its FIGURE 18 position. This movement involves a clockwise rotation of the gripper in FIGURES 17 and 18 whereby nose 92 rotates upward, bending and clamping the wire end W_b against an anvil 93 on the gripper block.

Gripper G rotates in a bore 95 in the gripper block. The gripper is rotated through a fraction of a turn by an arm 96 connected with a piston rod 97 in an air cylinder 98. The other end of cylinder 98 is connected by pin 99 with a bracket 100 on the plate 40. The bottom face of gripper block 90 is flush with the lower edge of plate 40, these two under surfaces (upper surfaces in FIGURES 19 to 21) engaging the top of the box as a bundle clamp when the frame 20 is lowered.

Beyond the gripper, the gripper block 90 contains a single wire guide channel 101 for the first pass wire portion Wa. The wire is retained in the channel by a plate 102 actuated by a spring 103, the edge of the plate being bevelled so that the wire will shift the plate and strip itself out of the groove when tensioned downwardly (upwardly in FIGURE 12).

Twister gear T is driven through the train of gears shown in FIGURE 15 from an intermediate gear 105. Gear 105 is rotated by a rotary air motor 106 through a clutch 107. Clutch 107 is engaged and disengaged by the reciprocating movement of a yoke 108 connected with a lever arm 109 pivotally mounted at 109a. This arm is rotated by an air cylinder 110 having a piston rod 111 connected with a clevis 112 on the arm. The air supply for cylinder 110 is connected to the air supply for motor 106 so that the clutch is engaged when the motor is started and disengaged when the motor is stopped.

On opposite sides of twister gear T in FIGURE 15 are movable wire guides 115 and 116 which are identical except that the guide 115 is slightly longer than guide 116. Guide 115 supports and guides the wires between cutter C and the twister gear while guide 116 supports and guides the wires between the twister gear and gripper G. Each of these guides has upper and lower guide slots 117 and 118 as shown in FIGURES 23 to 25. Each of these guides is mounted on an individual sector gear 119 for rotation on an individual stub shaft 120. The sector gears are rotated in unison by a pair of racks 121 on a vertical slide 122 reciprocated by a piston rod 123 in a cylinder 124. The upper end of cylinder 124 is connected with the air supply for feed motor 26 so that the guides 116 are moved to operative position as shown in FIGURE 23 during the forward feed movement of the wire and are retracted as shown in FIGURES 24 and 25 at all other times.

In the FIGURE 23 position, upper guide slot 117 is aligned with channel 41 in FIGURE 13 and gripper groove 91 in FIGURES 19 and 20 while lower guide slot 118 is aligned with channel 42 in FIGURE 13 and wire end Wb in FIGURES 19 and 20.

FIGURES 23 to 25 also illustrate the twister gear index assembly. Referring first to FIGURE 15, a large gear 130 is meshed with driving gear 105 in suitable ratio to make approximately one revolution in a wire splicing operation. In the present gear train, the twister gear T makes four plus a fraction revolutions to form a twisted wire splice but the number of twists may be varied as will be understood in the art. The shaft of gear 130 carries an indexing cam 131 and a switch cam 132 for operating the switch LS-3. Cam 132 is cylindrical except for a single high point 133 which actuates and then releases the said switch once in each revolution. As shown in FIGURES 23 to 25 indexing cam 131 has a deep forward stop shoulder 135 and a shallow reverse stop shoulder 136.

The twister gear has a wire receiving slot 140 which is indexed to wire receiving position by the mechanism now to be described. In wire receiving position the slot 140 is directed straight down which is the position assumed by the slot in FIGURE 23. In this position of the parts stop shoulder 135 is in engagement with roller 141 on stop arm 142. Stop arm 142 is pivotally mounted on a slide block 143 which may be raised by a cam lever 144 so that the roller 141 will clear the cam 131. As best shown in FIGURE 15, cam lever 144 is pivotally mounted at 145 on plate 40 for actuation by a piston rod 146 in a cam lever cylinder 147. When this cylinder is not energized the end of cam lever 144 connected with the piston is raised by spring 148 to hold the slide block 143 in its lower position shown in FIGURE 23. Two switches, LS-1 and LS-2, are actuated by the piston end of cam lever 144.

In this lower position of slide block 143 a plunger 150 mounted in a bore in the slide block is aligned with

switch LS-4 mounted on the back of plate 40. This plunger is urged to the left against stop arm 142 by a spring 151. Spring 151 thus operates through plunger 150 and stop arm 142 to rotate cam 131 counterclockwise to an index position wherein stop shoulder 136 engages pawl 155. Pawl 155 is pivotally mounted at 156 on a bracket 157 on plate 40 and is urged against cam 131 by a compression spring 158.

In a wire splicing operation motor 196 is energized, clutch 107 is engaged and piston rod 146 is actuated to raise stop arm 142 clear of the cam 131 allowing the twister gear to rotate clockwise. This rotation has commenced in FIGURE 24 and cylinder 124 has retracted the wire guides 115 and 116. Just prior to a complete revolution of gear 130 and cam 131 the cam lobe 133 actuates switch LS-3 to operate the cutter. While incidental switching and valving operations are taking place, cylinder 147 is deenergized allowing spring 148 to depress the slide block 143 to its FIGURE 25 position, placing stop arm 142 in a position to intercept cam stop shoulder 135. When shoulder 135 engages roller 141, stop arm 142 is moved to its limit position as shown causing plunger 150 to actuate switch LS-4 to stop motor 196 and disengage clutch 107. It also opens the gripper to release the wire and causes the wire guide frame to raise. Clockwise rotation of cam 131 is arrested in FIGURE 25 by the engagement of roller 141 with rubber bumper 141a, shown in FIGURE 23.

In this position of the cam the wire slot 140 in the twister gear has rotated past its vertical wire receiving and wire ejecting position to produce about 45° of over-twist in the splice as is customary in the art. In this position of the parts it will be observed that stop shoulder 136 has rotated slightly beyond the end of pawl 155. Spring 151 now acts on plunger 150 and stop arm 142 to reverse the rotation of cam 131 and gear 130 through a small angle until stop shoulder 136 engages pawl 155 with the parts returned to their starting position shown in FIGURE 23. Wire slot 140 in the twister gear is now directed straight down in its wire ejecting and wire receiving position and the cycle is completed. Wire guides 115 and 116 remain retracted until another length of wire is fed around the oval guide track. The twisted portions of the splice occupy the spaces made available by retraction of these guides.

The cutter assembly C is illustrated in FIGURES 26 to 30, the details of construction being best shown in the exploded view in FIGURE 31. Cutter block 175 has an upper cylindrical wire guide channel 41a aligned with the guide channel 41 in FIGURE 13 and a slotted guide channel 42a aligned with the channel 42 in FIGURE 13. The bottom side of the latter channel is closed by a plate 176 which carries a journal pin 177 for a bell crank arm 178. The short end of the bell crank arm has a round nose 179 for reciprocating a cutter bar 180 in a guide groove 181 in the cutter block. The nose 179 enters into a notch 182 in the cutter bar. At one side of notch 182 is an inclined face 183 which presents a shearing edge slidable along the guide surface in groove 181 through which the guide channel 41a emerges as best shown in FIGURES 26 and 28. This shearing edge does not extend down to the channel 42a so when there is a pair of wires Wa and Wb in these guide channels, only the upper wire Wa will be cut. The parts are held in assembled relation by a setscrew 184 in the threaded bore 185 engaging a flat surface 186 on journal pin 177.

Referring back to FIGURES 15 and 16, bell crank arm 178 is actuated by a link 188 connected with a crank arm 189 on a shaft 190. Shaft 190 is actuated through a small angle of rotation by a crank arm 191 connected with a piston rod 192 in a cylinder 195. The other end of cylinder 195 is pivotally connected with a bracket 196 on the plate 40.

Wire feed and tensioning in the FIGURE 1 machine
FIGURES 32 to 41 illustrate the mechanical operation

of the machine in FIGURES 1 to 3 in applying the wires W_1 and W_2 through the pallet openings in FIGURE 3a.

In FIGURES 32 and 33 the gates 70 are closed through the pallet openings and the wire is being pushed around the guide track in guide frame 20 by the feed motor. The first pass W_a extends through cutter C, twister gear T and is sliding freely through gripper G. The yieldable guide track section 50 is retracted to its normal position by elastic tensioning unit 53 and the leading end W_b is moving to the left through the gates 70 to complete its circuit around the oval track. FIGURE 34 is diagrammatic, the cutter and twister gear being turned through right angles relative to the gripper G to best show the wire position in the first pass through these elements.

In FIGURES 35, 36 and 37 the leading wire end W_b has made a second pass through the cutter and twister gear and its movement has been arrested by the gripper, causing the oncoming wire to push out yieldable track section 50, actuating the switch LS-6. A number of operations have taken place following this switch actuation. First, the reversing valve for the feed motor 26 has been actuated causing the feed motor to decelerate in preparation for reversal. Next, the guide track gates 70 have been opened by cylinders 75 stripping the wire from the guide track sections in the gates. Also, the gripper G has been actuated to bend up the wire end W_b and clamp it against the anvil 93.

When the feed motor 26 reverses, the excess loop of wire is retracted from the displaced position of yieldable track section 50 and this section returns to its normal position as shown in FIGURE 38. The reverse feed movement of the wire attempts to strip the wire from the guide track around the first bend of the oval in yieldable section 50 but stripping is prevented by the bar 56. This causes the wire to pull out and strip itself first from the remote or left end of the oval track with the wire remaining in the guide track around the first bend at the right end of the guide track, as shown in FIGURE 38.

As the wire starts to pull tight around the left bottom corner of the box in FIGURE 39, it strips itself from the lower guide track sections between the gates 70 and the lower part of the bend on the right side of the guide track as shown. As the stripping action continues past the last cover leaf 64 (FIGURE 9) it slides up the ramp surface 60 on the end of bar 56 and strips itself out of this part of the guide track between the forward face of bar 56 and the cover plate leaves 57. It is important to observe, however, that before this stripping action occurs from the yieldable guide track section 50 most of the slack has already been pulled back from the left end of the oval track and the wire on the left side of the box has assumed a position closely approaching the side of the box.

As the stripping of the wire progresses, the frame 20 is pulled down by cylinders 23 in FIGURE 1 causing the fastening head to engage the top of the box as shown in FIGURE 40. This allows more slack wire to be taken in from both sides of the box completing the slack pulling phase of the return feed movement and beginning a wire tensioning phase in which the wire is pulled tightly around all four corners of the box. The traction on the wire exerted by diaphragm unit 27 is sufficient to prevent feed rollers 35 from slipping, causing feed motor 26 to stall, the tension at stall being regulated by a pressure regulator in the air supply to the feed motor.

When the feed motor stalls, a pressure surge in its supply line actuates a pressure responsive switch. This switch initiates operation of the twister gear to splice together the overlapped portions of the wire. As the twister gear completes its operation it actuates a switch to operate the cutter C severing the wire from the source of supply. At the same time the wire guide frame 20 is raised back to its original position shown in FIGURE 41. This movement strips the splice from the twister gear freeing the box for movement to its next binding position or for movement out of the binding machine.

Control system

FIGURES 42 and 42a illustrate the electrical and pneumatic control system for the machine in FIGURE 1. The top of the diagram in FIGURE 42a fits the bottom of the diagram in FIGURE 42 to complete a single diagram of the electrical and pneumatic circuits. Electrical circuits are shown in solid lines while air conduits are shown in broken lines.

The various rotating and reciprocating pneumatic motors are energized from a compressed air conduit 300. The compressed air from its source of supply first passes through a filter 301, a pressure regulating valve 302 and a conventional lubricator 303. A first branch line 304 passes through a pressure regulating valve 305 to guide frame solenoid valve SV-2 which controls the admission of air to the upper or lower ends of the double acting lift frame cylinders 23 in FIGURE 1.

A second branch line 306 passes through an adjustable pressure-regulating valve 307 to wire tension solenoid valve SV-1. A conduit 309 from this valve supplies air to the rotary air motor 26 in FIGURE 1 for driving the motor in a reverse direction to strip the wire from the guide frame and tension the wire about the bundle. Motor 26 is driven in a forward direction to feed the wire for making the preformed loop by a different supply conduit 310 which continues from FIGURE 42a. The air supply in this conduit is controlled by wire feed solenoid valve SV-7 supplied through an adjustable pressure-regulating valve 311 from a branch line 312 of the main supply conduit 300. Branch line 312 has another branch 313 connecting with gate solenoid valve SV-8 which supplies the double acting gate cylinder 75 in FIGURE 5.

Conduits 309 and 310 (FIGURE 42) also connect with the opposite ends of wire guide actuating cylinder 124 in FIGURE 23 to place the wire guides 115, 116 in operative position during wire feed.

Another branch line 314 (FIGURE 42a) from the main supply conduit 300 connects with gripper solenoid valve SV-6 which controls the double acting gripper cylinder 98 in FIGURE 15.

Another branch line 315 connects with cutter solenoid valve SV-5 which controls the double acting cutter cylinder 195 in FIGURE 15.

Another branch line 316 passes through an adjustable pressure-regulating valve 317 to twister solenoid valve SV-4. This valve supplies twister motor 106 and the single acting clutch cylinder 110 in FIGURE 15. The piston of the clutch cylinder is spring returned when the air pressure is released.

Another branch line 318 connects with cam lever solenoid valve SV-3 which supplies the single acting cylinder 147 in FIGURE 15.

The electrical control system is energized from a two-wire source of supply 320 in FIGURE 42. One of the wires 321 connects with a manual-automatic selector switch 322 for connecting wire 321 with either the wire 323 or the wire 324. Wire 323 is used for manual push button operation while wire 324 provides complete automatic operation. The other side of the source of supply is connected with a wire 325.

Wire 324 has a branch 330 connecting with conveyor re-start limit switch LS-8 which has a wire 331 controlling the conveyor motors 16 and 18 in FIGURE 3. This limit switch, which is actuated by the wire guide frame, is shunted by a push button switch 332. This motor circuit is not shown in detail.

Guide frame solenoid valve SV-2 is actuated in one direction by a down solenoid 335 which is energized through a wire 336. The circuit may be closed through this wire either by a manual push button switch 337 or the gate limit switch LS-7 in FIGURE 5. Wire 336 also energizes wire tension relay solenoid R1 to close a double pole, single throw switch 337. Solenoid valve SV-2 is actuated in the opposite direction by an up solenoid 338 which is energized by wire 340.

One pole of relay switch 337 closes a holding circuit for wire 336 while the other pole closes a circuit to a wire 341. The circuit through wire 336 is completed through pressure switch PS-1. This pressure switch is opened by the increase in pressure in the wire tensioning air supply conduit 309 at a point close to air motor 26 when the latter tensions to stall.

The wire tensioning air supply is controlled by solenoid 345 in solenoid valve SV-1. This solenoid is energized by wire 341 either through a push button switch 347 or one pole of the double pole switch 337 of wire tension relay R-1. Switch 347 is connected with the wire 323 while the switch 337 is connected with the wire 324.

Cam lever relay solenoid R-2 is energized by a wire 350. The circuit through this wire is initially made either through the lower contact of pressure switch PS-1 or a push button twist-start switch 351. After energization of the solenoid, a holding circuit is maintained through one pole of relay switch 348 and cam lever limit switch LS-1. The other pole of relay switch 348 makes a circuit from wire 324 to a wire 346.

In FIGURE 42a wires 323, 324, 346, 340, 325 and 336 continue from the bottom of FIGURE 42.

The solenoid 360 of cam lever solenoid valve SV-3 is energized directly across the wires 325 and 346. The solenoid 361 of twister motor solenoid valve SV-4 is energized by a wire 362. The circuit is closed through wire 362 by one pole of a double pole relay switch 363 associated with the twister motor relay solenoid R3. Solenoid R3 is energized by a wire 364. The circuit through this wire is initially closed by twist-start switch LS-2 and a holding circuit is maintained by the other pole of relay switch 363 and twist-stop limit switch LS-4. Limit switch LS-4 has a lower contact connecting wire 324 with wire 340 through a wire 365. Wire 365 may also be energized from wire 323 by reset push button switch 366.

The solenoid 370 of cutter solenoid valve SV-5 is energized by a wire 371. This circuit may be completed through cutter switch LS-3 to wire 324 or through one pole of a double pole reset switch 372 to wire 323. The other pole of reset switch 372 connects wire 323 with a wire 373.

Gripper solenoid valve SV-6 is actuated in one direction by an open solenoid 368 energized directly across wires 325 and 340. This solenoid valve is actuated in the opposite direction by a close solenoid 369 energized through wire 373. Wire 373 has a branch connected with one contact of single pole, double throw wire feed stop limit switch LS-6.

Wire feed relay solenoid R5 operates a double pole, single throw switch 375. This solenoid is energized by wire 376. The circuit may be completed or maintained to wire 376 in various ways. Push button re-thread switch 377 connects wire 376 with wire 324. Wire 376 also connects with one pole of relay switch 375 which is in series circuit with one contact of wire feed stop limit switch LS-6. The other contact of this double pole switch is connected with time delay circuit wire 379. Wire 376 also energizes the time delay relay solenoid TD-2.

Solenoid 378 actuates the forward contactor 380 for the wire reel motor 31 in FIGURE 1. Solenoid 381 for the reverse contactor 382 is energized directly across the wires 325 and 336. The power supply for reel motor 31 is indicated at 385.

Solenoid 386 of gate solenoid valve SV-8 is energized by a wire 387 which also energizes the solenoid 388 of wire feed solenoid valve SV-7 and wire reel motor forward solenoid 378. This circuit, which is energized through wire 379 and relay switch 375 from wire 324, is maintained for a predetermined interval by time delay relay switch 390 if it is not sooner deenergized by LS-6. The circuit may also be energized manually through wire feed jog switch 391 from wire 323.

Wire 376 is normally energized initially from wire 324 through the conveyor limit switches CLS-10 and

CLS-11 as shown. Other contacts in these limit switches are arranged to connect wire 324 with a wire 395 controlling the conveyor motors 16 and 18 in FIGURE 3. Switches CLS-10 and CLS-11 are actuated by the box to stop the conveyor motors when the box is in position to receive the bands W₁ and W₂, the wire 395 being connected with a stop relay coil, not shown. Switch LS-8 and wire 331 in FIGURE 42 are similarly connected to a re-start relay coil to move the box forward from one binding position to another or to move the box out of the binding machine.

Operation of control system

The operation of the vertical machine in FIGURE 1 will now be described with reference to the sequence diagrams in FIGURES 32 to 41 in conjunction with the system drawings in FIGURES 42 and 42a.

When switch 322 is set for automatic operation, the wire 324 is energized from wire 321 as shown in FIGURE 42. When the box reaches its first binding position to receive a band W₁ through its pallet openings, it momentarily actuates limit switch CLS-10 (FIGURE 42a) energizing wire feed relay solenoid R5 and time delay relay solenoid TD-2 through wire 376. Relay switch 375 immediately closes and normally closed time delay switch 390 remains closed for an interval more than sufficient to complete the threading of the wire around the oval guide track. The closing of switch 375 operates gate solenoid valve SV-8 to actuate gate cylinder 75 to close the gates 70 in the lower side of the wire guide track. Relay switch 375 also operates the wire feed solenoid valve SV-7 to supply air pressure to conduit 310 driving feed motor 26 forward. Cylinder 124 operates to move retractable wire guides 115 and 116 to operative position. Relay switch 375 also energizes contactor solenoid 378 to start the reel motor 31 in a forward direction. This is the phase of operation illustrated in FIGURES 23 and 32 to 34.

When the wire completes its circuit around the guide track, movement of the leading end is arrested by the gripper causing the yieldable guide track section 50 to deflect outwardly and shift feed stop limit switch LS-6 from its upper to its lower contact in FIGURE 42a. This breaks the holding circuit for wire feed relay solenoid R5 allowing relay switch 375 to open, deenergizing the solenoids 386 and 388 of the gate and wire feed solenoid valves SV-8 and SV-7 and deenergizing contactor solenoid 378 to stop reel motor 31. The valves referred to are spring return valves which thus return to their original positions causing gates 70 to open and wire feed motor 26 to stop. The opening of gates 70 strips the wire therefrom and swings the gates clear of the pallet runners.

In case there is some fault allowing the wire to escape from the guide track so that yieldable section 50 is not deflected outward to actuate wire feed stop limit switch LS-6, the same function is performed after a short interval by time delay switch 390 to open the gates and stop the wire feed as well as reel motor 31.

The engagement of wire feed stop limit switch LS-6 with its lower contact in FIGURE 42a energizes the gripper close solenoid 369 in gripper solenoid valve SV-6 to operate the gripper cylinder 98. At approximately the same instant, gate limit switch LS-7 (FIGURE 42) is closed by the opening of gates 70 energizing the down solenoid 335 of guide frame solenoid valve SV-2 and the wire tension solenoid R1 of relay switch 337. This phase of the operation is illustrated in FIGURES 35 to 37.

The operation of guide frame solenoid valve SV-2 connects fluid pressure to the upper ends of cylinders 23 in FIGURE 1 to start lowering the guide frame 20. The closing of relay switch 337 energizes wires 336 and 341. Wire 336 energizes contactor solenoid 381 to reverse the reel drive motor 31 and start winding wire back on

the reel. In the meantime, wire 341 has energized wire tension solenoid valve SV-1 to operate feed motor 26 in reverse to draw back and tension the wire. Reversal of the wire feed immediately allows yieldable guide track section 50 to close, returning wire feed stop switch LS-6 to its original position in FIGURE 42a without affecting the gripper. Air pressure in wire tension conduit 309 operates cylinder 124 to retract wire guides 115 and 116 but does not operate pressure switch PS-1 because of the pressure drop in conduit 309 when feed motor 26 is running. Thus, the preformed loop is drawn back and tensioned about the bundle as previously described in connection with FIGURES 38 to 40.

In FIGURE 40 fastening head 40 bears against the top of the box clamping the box against the conveyor rollers, and motor 26 has substantially completed the wire tensioning phase of operation. When motor 26 can pull no more wire from the loop about the box, it stalls causing a pressure surge through the pneumatic conduit to pressure switch PS-1 which actuates this switch breaking the holding circuit for wire tension relay R1 and making a new circuit through wire 350 to energize cam lever relay R2 (FIGURE 42). This opens relay switch 337 shutting off the air supply for motor 26 and leaving the wire guides 115, 116 in retracted position. The opening of relay switch 337 also deenergizes wire 336 which opens contactor 382 in FIGURE 42a to stop the reel motor 31.

The energization of cam lever relay R2 closes a holding circuit for this relay through cam lever switch LS-1 and energizes wire 346 leading to FIGURE 42a. Wire 346 now energizes solenoid winding 360 in cam lever solenoid valve SV-3 to admit air into the single acting cylinder 147 in FIGURE 15. The resulting movement of cam lever 144 raises slide block 143 from its lower position in FIGURE 23 to its raised position in FIGURE 24 and actuates the two switches LS-1 and LS-2 in FIGURE 15, opening LS-1 and closing LS-2. The opening of LS-1 deenergizes cam lever relay R2 allowing relay switch 348 to re-open and shut off the air for cylinder 147. Spring 148 in FIGURE 15 then tends to lift the outer end of cam lever 144 causing roller 141 to bear against cam 131 behind its stop surface 135, the cam meanwhile having started to rotate clockwise as indicated in FIGURE 24. This rotation is produced by the closing of switch LS-2 which energizes twister motor relay R3 closing relay switch 363.

The closing of relay switch 363 establishes a relay holding circuit through the closed twister stop switch LS-4 and energizes solenoid winding 361 of twister motor solenoid valve SV-4. This admits air to twister motor 106 and clutch cylinder 110 to rotate the twister gear train.

A few degrees prior to completion of the splice twist in FIGURE 25, cam lobe 133 closes cutter switch LS-3 to operate the cutter and sever the splice from the source of wire supply (FIGURE 42a).

At the completion of the splice, twister stop switch LS-4 is actuated by cam 131 as shown in FIGURE 25. This actuation shifts the switch arm in FIGURE 42a, breaking the holding circuit for twister motor relay R3 and energizing wires 365 and 340. With the deenergization of twister motor relay R3, switch 363 opens cutting off the air supply to twister motor 106 and clutch cylinder 110 whereupon, with the twister motor clutch disengaged, spring 151 reverses the cam 131 in counter-clockwise rotation from its FIGURE 25 position back to its FIGURE 23 position relieving the over-twist and indexing twister gear slot 140 in a downward direction. At the same time, wire 340 energizes open solenoid winding 368 of gripper solenoid valve SV-6 to actuate gripper cylinder 98 for opening the gripper.

The energization of wire 340 also energizes up solenoid winding 338 in guide frame solenoid valve SV-2

in FIGURE 42 to actuate cylinder 23 for raising the guide frame 20 to its FIGURE 41 position. This strips the splice from the twister gear and frees the box for further movement on the conveyor. Switch LS-3 is closed by the rising of the guide frame to energize wire 331 in FIGURE 42 for restarting the conveyor motors.

When the box has moved to position for receiving its second band W₂, it actuates conveyor limit switch CLS-11 in FIGURE 42a to repeat the cycle just described. Now, when switch LS-8 is operated at the completion of the binding cycle for wire W₂, the conveyor motors continue to operate carrying the box away from the machine and bringing up a new box which will be stopped in its first binding position when it actuates conveyor limit switch CLS-10. Thus, the application of the transverse vertical wires W₁ and W₂ through the pallet openings is entirely automatic. A single one or any number of wires may be applied by providing conveyor limit switches such as CLS-10 and CLS-11 to stop a box in different binding positions.

The operation of the control system may be summarized briefly as follows with reference to the principal events which initiate the various functions. The closing of conveyor limit switch CLS-10 by the box closes guide frame gates 70, starts wire feed and reel motor forward, moves wire guides 115, 116 into operative position and initiates the delay interval of time delay switch 390.

The completion of wire feed actuates limit switch LS-6 opening gates 70, closing the gripper and stopping the wire feed and reel motor. In case of fault, if the wire continues to feed without actuating limit switch LS-6, these functions are performed by time delay switch 390.

Opening of gates 70 closes limit switch LS-7 which lowers the guide frame, reverses the wire feed motor and reel motor and retracts the wire guides 115, 116.

Stalling of the wire feed motor on tensioning operates pressure switch PS-1. This shuts off the air supply to the motor, stops the reel motor and starts the twister motor.

The twister mechanism closes the cutter switch, then actuates the twister stop switch, opens the gripper and raises the wire guide frame.

Rising of the guide frame closes limit switch LS-8 to re-start the conveyor motors.

The control system also includes a number of push button switches for initiating the machine functions manually one at a time and for continuing the automatic cycle at various intermediate points when the automatic cycle has been interrupted for some reason. The specific functions accomplished by these manual switches will be apparent from the wiring diagram and the foregoing description of the normal automatic operation.

As previously explained, selector switch 322 in FIGURE 42 is placed in its lower position to energize wire 324 for full automatic operation. Some of the push button switches energize circuits from this wire for performing various individual functions, as for example in re-thread, or completing an automatic cycle after an interruption of the cycle. Other of the push button switches energize circuits from wire 323 for individual automatic functions, requiring selector switch 322 first to be placed in its upper position for hand operation without the full automatic cycle.

Push button switch 332 starts the conveyor to move the box. Switch 337 is a cycle switch which starts wire tension and moves the guide frame down. Closing this switch will result in twisting a splice when selector switch 322 is in automatic position. Switch 347 is a wire tension jog switch and switch 351 is a twist start switch.

Push button switch 372 in FIGURE 42a may be designated as reset No. 1. Closing this switch operates the cutter and closes the gripper when selector switch 322 is set for manual operation. Switch 366 is designated as reset No. 2. Closing this switch opens the gripper and raises the wire guide frame to free the box for movement by the conveyor.

Switch 377 is a re-thread switch. Closing this switch

when selector switch 322 is in automatic position feeds the wire into position for tying. Switch 391 is a wire feed jog switch operable when selector switch 322 is in manual position.

It is to be noted that the machine has a single gripper and a single cutter, resulting in a considerable simplification in mechanical parts as well as in the control system as compared to conventional binding machines having two grippers and two cutters. The gripped end of the wire is retained on the splice and does not create a problem of disposal to keep short cut ends out of the mechanism. The retractable wire guides on opposite sides of the twister gear guide the wire unfailingly during feed movement and then retract to provide free twisting spaces for the length of splice desired. The whole fastening head is relatively simple and compact permitting the use of a plurality of guide frames and fastening heads side by side for the simultaneous application of a plurality of parallel bands, if desired.

Longitudinal and horizontal bindings

The description to this point has involved the machine shown in FIGURES 1, 2 and 3 for applying the transverse vertical wires W_1 and W_2 through the pallet openings. A similar machine applies the longitudinal wires W_3 and W_4 except that guide track gates 70 are not necessary whereby the guide track may continue uninterrupted across the lower side of the frame 20. The binding cycle starts in a different phase of the operation and may be accomplished more quickly because the wire feed may take place at the end of the binding cycle instead of at the beginning. The box is rotated through 90° upon leaving the machine in FIGURES 1 to 3, the pallet runners 10 being wider than the spacing of the rollers 17 so that the box can approach the second machine in a transverse position on the roller conveyor. In view of its close similarity to the first machine, the second machine which applies the wires W_3 and W_4 is not specifically illustrated.

The binding cycle for applying one of the wires W_3 or W_4 starts with the wire already fed into guide frame 20 with its end secured in the gripper. When the box is positioned in the bundle opening of the guide frame the first operation is to move the guide frame down to clamp the bundle under the fastening head. Feed motor 26 starts in reverse at the same time stripping the preformed loop of wire from the guide track so that by the time the box is clamped by the fastening head, the wire has been stripped from the guide track and is being tensioned about the bundle as in the case of the phase of operation of the first machine shown in FIGURE 40. The final tensioning, splicing and cutting steps are then performed in sequence as hereinbefore described, and guide frame 20 is shifted by cylinders 23 back to its upper position, freeing the box for movement to receive another longitudinal binding or for movement out of the machine the same as shown in FIGURE 41.

During this upward movement of the guide frame 20 and the positioning of the same box or a different box for binding in the bundle opening, feed motor 26 operates in forward direction to re-thread the guide track with a new length of binding wire. As soon as the end of the new binding wire reaches the gripper G the yieldable guide track section 50 swings out, operating wire feed stop switch LS-6 in FIGURE 4. In this case, switch LS-6 merely operates the gripper G to secure the free end of the wire and the machine is shut off with the completion of this function to be in readiness for the next binding cycle. Thus, the wire feed is accomplished during the time required for placement of the bundle whereby there is less delay in the movement of the bundle.

The third machine which applies the horizontal binding W_5 in FIGURE 3a is illustrated in FIGURES 43 to 45. Roller conveyor 200 is driven by motor 201. Since the box has not been turned after leaving the second machine which applied the wires W_3 and W_4 , the pallet run-

ners 10 are parallel with the conveyor rolls and the box travels transversely in the direction of the arrows in FIGURES 43 and 45. The orientation of the box is immaterial, however, as it may approach the third machine either endwise or sideways.

The third machine comprises a stationary frame 202 having four vertical posts 203 forming guides for a vertically movable guide frame 205. Guide frame 205 is similar to the guide frame 20 in FIGURE 4 except that it is disposed in a horizontal plane and does not include the gates 70. The guide frame is equipped at its corners with pairs of grooved rollers 206 which embrace opposite sides of the posts 203. The guide frame is suspended by pairs of chains 211 and 212 trained around pulleys 213 and 214 to sprocket wheels 215, 216. The ends of the chains are anchored to these sprocket wheels so that the sprocket wheels will take up the chains in the manner of a drum hoist to raise and lower the guide frame. Sprocket wheels 215, 216 are keyed to a shaft 217 which is driven by a sprocket wheel 218 at one end of the shaft. Sprocket wheel 218 is driven by a chain belt 219 from motor 220.

When guide frame 205 is raised to its upper position in FIGURES 44 and 45, it clears the box B so that the box will pass under the guide frame. Then the guide frame is lowered to its lower position shown in these figures in surrounding relation to the box.

Various movements are involved in positioning the box to receive its horizontal binding W_5 . As the box approaches the machine, guide frame 205 is in its upper position. Motor 201 is controlled by a conveyor limit switch to stop the box on the conveyor at a point below the approximate center of the guide frame opening. Then the guide frame lowers to the level desired for the plane of the binding which is indicated by the lower position of the guide frame in FIGURES 44 and 45. Then the box is moved forward by motor 201 until its leading side engages fastening head 40 and bumper 221.

The wire guide frame contains a preformed loop of wire in readiness for a binding cycle and this cycle is started when the leading edge of the box touches the fastening head. This machine performs the same cycle as the second machine, which applies the wires W_3 and W_4 , first retracting and stripping the wire from the wire guide track, tensioning it about the bundle, forming a twisted wire splice and cutting off the splice from the source of supply. When the cutter has finished its operation, this cycle is completed, actuating a switch to reverse motor 201 momentarily, sufficiently to return the box to the center of the opening in guide frame 205. This reverse movement of the bundle strips the splice from the twister gear and causes the box and binding to clear the fastening head. Guide frame 205 is then raised by motor 220 to its upper position above the level of the box and when it reaches this position a switch is actuated to start motor 201 in a forward direction carrying the box out of the machine.

While these last movements are taking place, subsequent to the stripping of the splice from the twister gear, feed motor 26 is energized in a forward direction to feed a new length of wire into the wire guide track. When the leading end of the new length of wire reaches the gripper, its movement is arrested and the deflection of yieldable guide track section 50 actuates switch LS-6 in FIGURE 4 to operate the gripper G securing the end of the wire. The feeding and gripping operations are completed before the next box arrives and the fastening head mechanism is at rest while awaiting its arrival.

The horizontal binding machine shown in FIGURES 43 to 45 is capable of automatically placing a plurality of horizontal bands on the box at different levels, if desired. The first band is placed at the lowest level desired. Then, when this binding cycle is completed, motor 201 backs the box to the center of the guide frame opening to strip the splice from the twister gear. Then, instead of moving up to clear the box, the guide frame 205 merely moves up to the next higher binding level and stops in such position. The completion of this movement starts

motor 201 to move the box forward into engagement with the fastening head at the new level and the binding cycle is repeated. This sequence of operation may be repeated as often as desired to place any number of horizontal bands around the box one above another. Then, after the last and uppermost band has been secured, guide frame 205 moves up to clear the box and the box passes out of the machine as above described. The back and forth movements of the box, the up and down movements of guide frame 205 and the binding cycle are all initiated in predetermined sequence by limit switches in an extension of the type of control system shown in FIGURES 42 and 42a.

In some cases it is more practical to raise the box than to move the wire guide frame up and down, to produce the same result.

As previously explained, the control system is slightly modified for the second and third machines which do not have the gates 70 and limit switch LS-7. In these machines the feed and reel motors are reversed and wire guides 115, 116 are retracted at the beginning of the binding cycle. Thereafter the operation is the same as for the first machine until the guide frame rises at the end of the twister mechanism cycle. Then, in the second and third machines a limit switch actuated by the rising guide frame performs the function of conveyor limit switches CLS-10 and CLS-11 to start the wire feed and reel motor forward and move wire guides 115, 116 into operative position. The complete cycle ends at the completion of wire feed, the actuation of limit switch LS-6 then merely closing the gripper and stopping the wire feed and reel motor. Thus, this cycle starts with tensioning and ends with re-thread.

Having now described our invention and in what manner the same may be used, what we claim as new and desire to protect by Letters Patent is:

1. In a binding machine, a guide frame having a gripper and a guide track arranged to encircle a bundle, reversible feed means arranged to feed a band around said guide track to said gripper and then strip the band from said guide track and tension the band about the bundle, resilient cover means on said guide track following the first quarter turn permitting the band to strip itself from said following portions of the guide track when the band is tensioned by said feed means, a wall on the inside of said first quarter turn preventing stripping of the band from said first quarter turn in the initial tensioning and stripping of the band, and a sloping ramp surface on the end of said wall at the end of said first quarter turn guiding the band over one edge of said wall as stripping progresses from said following portions of the guide track back to said first quarter turn, and resilient cover means on said wall edge.

2. In a binding machine, an open center guide frame having a gripper and a guideway for a band making a circuit around said frame, means for feeding a band through said guideway to said gripper and for tensioning the band to strip it from the guideway, an outwardly yieldable section in the first quarter turn of said guideway, a wall on the inside of said first quarter turn to prevent initial stripping from said yieldable section, a sloping ramp surface on the trailing end of said wall to guide the band over an edge of said wall after the band has been stripped from the remainder of said guideway following said yieldable section, and resilient cover means for said guideway bearing on said wall edge to release the band after it has climbed said ramp, whereby the band may be tensioned about a bundle within said frame.

3. In a binding machine, an open center rectangular guide frame having a guideway for a band making a circuit around said frame, a fastening head including a gripper in one side of said frame, reversible feed means for feeding a band around said guideway to said gripper and for tensioning the band to strip it from the guideway and tension it about a bundle within said frame, said

guideway having a straight path from said feed means through said fastening head along said one side of the frame, the first quarter turn of said guideway from said straight path comprising an outwardly yieldable section pivotally mounted at its trailing end on said frame, means actuated by the outward movement of said yieldable section to operate said gripper, a wall on the inside of the turn at said yieldable section to prevent initial stripping from said yieldable section when the band is tensioned, a sloping ramp surface on the trailing end of said wall to guide the band over an edge of said wall after the band has been stripped from the remainder of said guideway following said yieldable section, and resilient cover means for said guideway bearing on said wall edge to release the band after it has climbed said ramp, whereby the band may be tensioned about a bundle within said frame.

4. In a binding machine, a rectangular open center guide frame mounted in a vertical plane, a fastening head in the upper side of said frame, the lower side of said frame having a plurality of notches therein to admit pallet runners spaced under a box within said frame, gates in said notches movable out of the plane of said frame, and a guide track for a band making a circuit around said frame and through said gates to span said notches, said gates being closable through the pallet runner spaces.

5. In a machine for applying a band around a box having pallet runners spaced from its bottom, an open center vertical guide frame adapted to encircle the box, the lower side of said frame having gaps to receive said pallet runners, gates in said gaps movable through said pallet runner spaces, and a guide track for a band making a circuit around said frame and through said gates to span said gaps when said gates are closed.

6. A preformed loop type of binding machine comprising a vertically movable open center wire guide frame having a wire guide track adapted to encircle a bundle, a wire feed air motor arranged to feed a wire around said guide track and to strip the wire from said guide track and tension the wire around the bundle, means to lower said frame to bundle clamping position, a twister mechanism in the upper side of said frame for splicing the wire, a gripper on one side of said twister mechanism for holding an end portion of the wire in said twister mechanism, a wire cutter on the opposite side of said twister mechanism, a pressure switch actuated by stall pressure in the air supply to said motor for shutting off said air supply after tensioning and starting said twister mechanism, and means actuated by said twister mechanism for operating said cutter, stopping said twister mechanism, opening said gripper and raising said guide frame.

7. In a preformed loop type of wire binding machine having a wire guideway adapted to encircle a bundle, a twister gear for splicing the wire, retractable wire guides on opposite sides of said twister gear, a reversible air motor for feeding the wire around said guideway and for stripping the wire from said guideway and tensioning it around the bundle, and a double acting cylinder for shifting said wire guides, one end of said cylinder being connected to the forward air supply for said motor to move the wire guides to operative position at the beginning of wire feed and the opposite end of said cylinder being connected to the reverse air supply for said motor to retract the guides at the beginning of wire stripping and tensioning.

8. A machine for binding a box through pallet runner openings at the bottom of the box comprising a vertical open center rectangular wire guide frame mounted for vertical movement, gates in the lower side of said frame to admit the pallet runners, said gates being closable through said pallet runner openings, wire feed and tensioning means arranged to feed a wire around said guide frame and through said gates when said gates are closed, means responsive to completion of wire feed to open said

gates, means actuated by the opening of said gates to reverse said feed means and lower said frame to clamp the top of the box, means responsive to wire tensioning for shutting off said tensioning means and splicing the wire, and means responsive to splicing of the wire for cutting the wire from its source of supply and raising said guide frame.

9. A machine for binding a box through pallet runner openings at the bottom of the box comprising a vertical open center rectangular wire guide frame mounted for vertical movement, gates in the lower side of said frame to admit the pallet runners, said gates being closable through said pallet runner openings when the frame is in an upper position, means for feeding a wire around said frame and through said gates when the gates are closed, said gates being openable after wire feed to permit said frame to be lowered to clamp the top of the box, and means for tensioning the wire and securing it around the box while the frame is in said lower position.

10. A machine for binding a box through pallet runner openings at the bottom of the box comprising a vertical open center rectangular wire guide frame mounted for vertical movement, gates in the lower side of said frame to admit the pallet runners, said gates being closable through said pallet runner openings when the frame is in an upper position, a conveyor arranged to move a box through said frame, means arranged for actuation by the box to close said gates and start wire feed around said frame and through said gates, a yieldable wire guide track section in said frame responsive to completion of wire feed to open said gates, means actuated by said gate opening to reverse said wire feed and lower said frame to clamp the box on the conveyor, means responsive to completion of wire tensioning to initiate splicing of the wire, means responsive to wire splicing to cut the wire from its source of supply and raise said frame, and means actuated by the rising of said frame to re-start the conveyor.

11. A preformed loop-type wire binding machine having a single wire gripper and a single wire cutter, said machine comprising a wire guide frame having a guide track arranged to encircle a bundle, feed means arranged to feed a wire around said guide track, said feed means being reversible to tension the wire about the bundle, a fastening head in one side of said frame, a slotted wire twister gear in said fastening head, said gripper being disposed on one side of said twister gear and said cutter being disposed on the opposite side of said twister gear, means to operate said twister gear, gripper and cutter, and a pair of retractable wire guides having wire receiving slots, one of said guides being disposed between said gear and said gripper and the other guide being disposed between said gear and said cutter, the spaces occupied by said guides defining the twisting length of a splice formed by said twister gear when said guides are retracted.

12. In a binding machine as defined in claim 11, means supporting said guide frame in horizontal position for binding a bundle in a horizontal plane, means for producing relative vertical movement between said guide frame and said bundle to place said frame around the bundle, and means for holding the bundle against said fastening head.

13. In a binding machine as defined in claim 11, a bundle conveyor, and means supporting said guide frame for vertical movement in a horizontal position above said conveyor to place said guide frame around a bundle on said conveyor for applying a horizontal binding.

14. In a preformed loop type of binding machine, a fastening head, a slotted wire twister gear in said fastening head, one only wire gripper in the machine, said gripper being on one side of said twister gear, means to feed a binding wire through said twister gear to said gripper, means to operate said gripper, one only wire cutter in the machine, said cutter being on the opposite side of

said twister gear, means to operate said cutter, and a pair of retractable wire guides having wire receiving slots on opposite sides of said twister gear between said gear and said gripper and cutter, the spaces occupied by said guides defining the twisting length of a splice formed by said twister gear when said guides are retracted, and means to actuate and retract said guides.

15. In a binding machine, an open center guide frame adapted to encircle a bundle, a fastening head including a gripper in one side of said guide frame, a guideway for a band making a circuit around said frame and through said fastening head, means for feeding a band around said guideway and through said fastening head to said gripper and for tensioning the band to strip it from the guideway and tension it about the bundle, a wall on the inside of the first quarter turn of said guideway beyond said fastening head preventing stripping of the band from said first quarter turn in the initial tensioning and stripping of the band and causing the band to strip first from portions of the guideway following said first quarter turn, a sloping ramp surface on the end of said wall at the end of said first quarter turn for guiding the band over one edge of said wall as stripping progresses from said following portions of the guide track back to said first quarter turn, and resilient cover means bearing on said wall edge to release the band after it has climbed said ramp.

16. In a binding machine as defined in claim 15, means for supporting said guide frame in horizontal position for binding a bundle in a horizontal plane, means for producing relative vertical movement between said guide frame and said bundle to place said frame around the bundle, and means for holding the bundle against one side of said guide frame.

17. In a binding machine as defined in claim 15, a bundle conveyor, and means supporting said guide frame for vertical movement in a horizontal position above said conveyor to place said guide frame around a bundle on said conveyor for applying a horizontal binding.

18. A preformed loop type of binding machine comprising a band guideway arranged to encircle a bundle, a twister gear arranged to receive a wire therethrough from said guideway, a single gripper in said machine, said gripper being on the wire emergent side of said twister gear, feed means arranged to feed a wire around said guideway through said twister gear and into said gripper, said gripper having an abutment to stop the end of the wire, an outwardly yieldable section in the first quarter turn of said guideway movable in response to continuation of the wire feed after the end of the wire has been stopped in said gripper to operate said gripper, a single cutter in said machine, said cutter being on the wire entrance side of said twister gear, means to reverse said feed means to strip the wire from said guideway and tension it about the bundle, means to operate said twister gear, and means to operate said cutter.

19. In a binding machine, an open center rectangular guide frame arranged to encircle a bundle, a band guideway making a circuit around said frame, a fastening head including a gripper in one side of said frame, feed means arranged to feed a band around said guideway, through said fastening head and into said gripper, said gripper having an abutment to stop the end of the band, said guideway having a straight path from said feed means through said fastening head along said one side of said frame, the first quarter turn of said guideway from said straight path comprising an outwardly yieldable section, said outwardly yieldable section being movable in response to continuation of the band feed after the end of the band has been stopped in said gripper to operate said gripper, and means to reverse said feed means to strip the band from said guideway and tension it about the bundle.

20. In a binding machine as defined in claim 19, means for supporting said guide frame in horizontal position for binding a bundle in a horizontal plane, means for pro-

ducing relative vertical movement between said guide frame and said bundle to place said frame around the bundle, and means for holding the bundle against said fastening head.

21. In a binding machine as defined in claim 19, a bundle conveyor, and means for supporting said guide frame for vertical movement in a horizontal position above said conveyor to place said guide frame around a bundle on said conveyor for applying a horizontal binding. 5

22. In a binding machine, a vertical guide frame having a gripper and a guide track arranged to encircle a bundle having pallet runners spaced from the bottom of the bundle, reversible feed means arranged to feed a band around said guide track to said gripper and then strip the band from said guide track and tension the band about the bundle, and a plurality of retractable guide track sections in the lower side of said guide track arranged to provide gaps in the guide track for admission of the pallet runners, said sections being movable through 15 the pallet runner spaces to establish continuity of the guide track around the bundle. 20
